UNITED STATES PATENT OFFICE.

JOSEPH R. VALENTINE AND ALEXANDER T. GRIGG, OF PUEBLO, COLORADO.

GAS-ENGINE.

SPECIFICATION forming part of Letters Patent No. 425,116, dated April 8, 1890.

Application filed December 24, 1889. Serial No. 384,900. (No model.)

To all whom it may concern:

Be it known that we, JOSEPH R. VALENTINE and ALEXANDER T. GRIGG, citizens of the United States, and residents in the city of 5 Pueblo, in the county of Pueblo, in the State of Colorado, have invented a new and useful Gas-Engine, of which the following is a description.

The invention relates to that class of engines in which the actuating-power is evolved through the combustion of a gaseous compound which is produced through the commingling of a hydrocarbon gas or vapor and a suitable volume of atmospheric air, the compound and the air being introduced under pressure, either separately or together, into the cylinder of the engine or into a chamber which is in direct communication with such cylinder.

20 The invention consists in certain novel parts and in certain novel combinations of parts in or in connection with a gas-engine, as will first be described in detail, and then specifically indicated in the claims.

25 In the accompanying drawings, Figure 1 represents in vertical longitudinal central section so much of an engine of the described character as is necessary to a clear understanding of our invention. Fig. 2 is a vertical transverse section of the vaporizing apparatus to which our invention in large part relates, the section being taken in the line $y-y$ in Fig. 1. Fig. 3 represents in longitudinal central section a modification in the construction of the vaporizing apparatus and its 30 inlet and outlet connections. Fig. 4 represents a further modification in the construction of the vaporizing mechanism, relating particularly to the means employed in introducing compressed air to the vaporizing-space. Fig. 5 is a transverse section in the line $z-z$ of Fig. 4. Fig. 6 represents in longitudinal central section a modified form of vaporizing-section in which the filling of felt and the 35 perforated cylinder are of equal length.

40 For the purposes of this invention the air-compression cylinder A and the power-cylinder B may in their leading elements be of any ordinary or approved construction, being provided with water-jackets a and b , respectively, and with ordinary inlet and outlet openings and appliances not necessary to be fully

shown for operating the movable parts. The air-compression cylinder has the usual provision of piston a' and inlet and outlet valves a^2 and a^3 , and the power-cylinder has piston b' , operating in connection with inlet-openings, to be described, and outlet opening and valve b^2 . Connecting the air-compression cylinder with the power-cylinder is the compressed-air pipe C, composed of longitudinal sections c^{10} , c^{11} , c^{12} , c^{13} , c^{14} , c^{15} , and c^{16} , as shown. The compressed-air pipe is provided in its section c^{12} with a diaphragm d , which has an opening and a valve-seat c' and closing-valve C' , and it is provided also in connection with the diaphragm and its opening with a lateral pipe c , which has a diaphragm d' , valve-seat c^2 , and closing-valve C^2 . At a point coincident with its longitudinal center the head of the power-cylinder is recessed to form the flame or combustion chamber F, while a corresponding portion of the end section c^{16} of the compressed-air pipe C is similarly recessed to form a mixing-chamber F', the inlet-opening f of which has seat f^2 , which is closed by valve f' .

45 The mixing-chamber F' and the combustion-chamber F are separated by a compound diaphragm G, which consists of inner and outer finely-perforated metallic plates g' and g^2 and an intermediate section g of fine wire-gauze, and which is suitably secured between the power-cylinder and the end section, as clearly seen in Fig. 1. At one side, 50 between the inlet-opening f and the compound diaphragm G, the mixing-chamber has a vapor-inlet opening or passage h^2 , and upon the opposite side of such diaphragm the combustion-chamber F is provided with a lighting opening and passage l , which is closed by a valve l' .

55 Between the sections c^{13} and c^{15} of the compressed-air pipe C, is secured the vaporizing apparatus c^{14} , the cylindrical outer shell c^{17} of which is, by preference, of somewhat greater diameter than the contiguous sections, and is provided with a series of interior longitudinal grooves or passages c^{18} in any desired number. Within this cylinder or outer shell c^{17} and coincident with the sections c^{13} and c^{15} is the tubular wick-like vaporizing screen or cylinder c^{19} , which is composed of woolen felt, while within the felt is fixed the inner

tube or cylinder c^{20} , which is formed from thin finely-perforated metal. The cylinder c^{17} has a tapped opening c^{21} to receive the threaded end of an oil-induction pipe E, the inner extremity of which, for a short distance, has a felt filling e, and it has also a similar opening c^{22} to receive one end of a vapor-ejection pipe H, which also is at this end preferably provided with a felt filling h. This vapor-pipe H, which at a suitable point is provided with a suitable regulating-valve or stop-cock h' , is by its opposite end connected to the mixing-chamber F', where it is coincident with the opening or short passage h^2 , already described.

As will be seen in Fig. 1, the filter or vaporizing-felt c^{19} is somewhat shorter than the parts c^{17} and c^{20} , between which it is embraced, thus providing an annular end chamber or passage c^{23} between the main passage of the compressed-air pipe C and the grooves c^{18} in the cylindrical shell c^{17} .

In the modified construction represented in Fig. 3 the oil-induction pipe and the vapor-ejection pipe are united at a point a short distance from the body of the shell c^{17} , the oil being fed inwardly and the vapor discharged outwardly through the short central pipe below their point of junction. This construction may in some instances be advantageously employed.

In Figs. 4 and 5 the chamber or passage c^{23} is represented as separated from the felt vaporizing-filling c^{19} by a metallic ring c^{24} , which has perforations p , and which is provided in its periphery with a series of notches or indentations c^{25} , which correspond with the longitudinal grooves c^{18} in the inner surface of the cylindrical shell c^{17} of the vaporizing apparatus c^{14} .

In Fig. 1 a short passage or connection a^4 opens into a reservoir (not shown) of suitable dimensions for compressed air.

It will be understood that neither the chamber c^{23} nor the series of grooves c^{18} in the shell of the vaporizing apparatus is essential to the successful operation of the same. While each constitutes a desirable feature, neither is indispensable. It will be obvious also that the pipe or passage for compressed air may be made up otherwise than of the several sections represented and described, the essential requisites being a pipe or equivalent passage for air and vapor from the air-compression cylinder to the power-cylinder and a vaporizing apparatus which constitutes a portion of such pipe or passage and which has communication with the combustion-chamber of such power-cylinder.

In the operation of the apparatus, the valve C' being closed and the valves C² and h' being opened, a suitable quantity of compressed air, forced through the lateral pipe c, which leads from a point behind to a point in front of the diaphragm d, will pass through the perforated cylinder c^{20} and into and through the felt filling c^{19} , breaking up and vaporiz-

ing the oil therein, and constituting in connection therewith an inflammable gaseous compound which finds its way in a fine stream through the pipe H and through the mixing-chamber F' into the combustion-chamber F, where, upon the application of a lighted match or other flame at the opening passage or lighting-port l, it will be instantly ignited. The valves l' and C² being therupon closed, the valve C' being opened, the pressure being increased, and the valve f' being operated at regular intervals through the medium of a suitable lever, (not shown,) which is actuated by the shaft of the engine, vapor and air commingled will be continuously supplied to the mixing-chamber F', and through it and through the diaphragm G to the combustion-chamber F, whence the expansive force is exerted to operate the piston b' in a well-known manner, the exhaust finding exit at regular intervals through the opening controlled by the outlet-valve b².

It will be understood that the space within the vaporizer and its conducting-pipe H, although not great, is yet ample to afford a continuous supply of the combustible compound sufficient to maintain the flame within the combustion-chamber, even if for a considerable space of time the injection of oil to the vaporizer should be discontinued.

The invention having been thus described, what is claimed is—

1. In a gas-engine, an air-compressing cylinder, a power-cylinder, a vaporizing apparatus which is exterior to the power-cylinder, and a tubular passage which connects the air-compressing cylinder with the power-cylinder, and which embraces the exterior vaporizing apparatus, in combination.

2. In a gas-engine, an air-compressing cylinder, a power-cylinder, and a tubular passage which connects the air-compressing cylinder with the power-cylinder, and which is composed in part of an intermediate vaporizing-section which furnishes the sole supply of combustible compound to the power-cylinder, and which is connected by two distinct and independent passages with such power-cylinder, in combination, for the purposes specified.

3. In a gas-engine, an air-compressing cylinder, a power-cylinder, a tubular passage which connects the air-compressing cylinder with the power-cylinder, and a vaporizing-section which constitutes an intermediate part of such tubular passage, and which is connected with the power-cylinder by two passages, one of which conducts the main vapor-supply and the other of which connects a restricted vapor-supply for the maintenance of a flame within the combustion-chamber of such power-cylinder, in combination.

4. In a gas-engine, an air-compressing cylinder, a power-cylinder, a tubular conducting-passage which leads from the air-compressing cylinder to the power-cylinder, and a vaporizing-section which constitutes an inter-

mediate part of such tubular conduit, and which is connected with the power-generating section of the power-cylinder by two passages, one of which conducts the main volume 5 of vapor, which is supplied at brief intervals, and the other of which conducts a restricted non-intermittent vapor-supply for maintaining a continuous flame within the combustion-chamber, in combination.

10 5. In a gas-engine, an air-compressing cylinder, a power-cylinder, a tubular passage which embraces a cylindrical vaporizing-section connecting the air-compressing cylinder with the power-cylinder, an oil-induction pipe 15 discharging into the cylindrical vaporizing-section, and a vapor-eduction pipe, which at its receiving end is connected with the cylindrical vaporizing-section, and which at its discharging end communicates with the combustion-chamber of the power-cylinder, in combination, substantially as and for the purposes set forth.

6. In a gas-engine, an air-compressing cylinder, a power-cylinder, a sectional tubular 25 passage which connects the air-compressing cylinder with the power-cylinder, and which embraces an oil-receiving and vapor-discharging vaporizing-section, and which embraces also a central valve-controlled opening for 30 the passage of the main air-supply, and a lateral valve-controlled passage for conveyance of a restricted air-supply, in combination, substantially as specified.

7. In a gas-engine, a tubular passage for 35 compressed air and for vapor, which is composed in part of a vaporizing-section which embraces a cylindrical outer shell, a foraminated inner cylinder, and an intermediate filling of felt.

40 8. In a gas-engine, a sectional conducting-pipe which embraces a cylindrical vaporizing apparatus in which are combined a foraminated inner cylinder, a cylindrical outer shell, an intermediate tubular filling of felt, 45 an oil-pipe which discharges through the outer shell into the felt filling, and a regulated vapor-discharge pipe which receives vapor from the space within which the felt is embraced.

9. In a gas-engine, a cylindrical vaporizing-50 section in which air is forced from the interior of the cylinder outwardly, and which embraces an imperforate outer shell, a foraminated inner cylinder, and an intermediate filling of felt which is shorter than the cylindrical parts 55 between which it is embraced, and whereby an annular chamber or passage for compressed air is formed, substantially as described and shown.

10. In a gas-engine, a cylindrical vaporizing-60 apparatus in which air is forced from within

laterally outward, which embraces a close outer shell which has interior longitudinal grooves, a foraminated inner tube or cylinder, an intermediate felt filling of smaller longitudinal extent than the closed outer shell, and 65 an annular end chamber which is coincident with the felt filling and which serves to insure the passage of compressed air to the longitudinal grooves in the outer shell.

11. In a gas-engine, an air-compressing cylinder, a power-cylinder, an intercommunicating main air-pipe which is provided with a diaphragm which has a valved opening, and a lateral auxiliary valved pipe which conducts air in restricted quantities from a point in 75 rear to a point in front of the diaphragm in such main air-pipe, in combination.

12. In a gas-engine, a vaporizing-section which constitutes a part of a compressed air and vapor passage, a power-cylinder which 80 has a combustion-chamber, an end section of such compressed-air passage which is provided with a mixing-chamber, a foraminated diaphragm between the combustion-chamber and the mixing-chamber, and a valved passage 85 which extends from the vaporizing-section to the mixing-chamber, in combination.

13. In a gas-engine, an air-compressing cylinder, a power-cylinder, an intercommunicating passage, a vaporizing apparatus which 90 constitutes a part of such intercommunicating passage and which is concentric therewith, a combustion-chamber at the entrance to the power-cylinder, a mixing-chamber between the compressed-air passage and the combustion-chamber provided with a valved opening 95 for the regulated injection of compressed air and vapor, a valved tubular passage connecting the vaporizing-chamber with the mixing-chamber, and a foraminated diaphragm between 100 the mixing-chamber and the combustion-chamber, combined for operation substantially as described.

14. In a gas-engine, a power-cylinder, a mixing-chamber having a regulated air and 105 vapor injecting opening, a combustion-chamber at the entrance to the power-cylinder, a foraminated diaphragm which separates the mixing-chamber from the combustion-chamber, a vapor-injecting pipe which discharges 110 into the mixing-chamber, and a lighting passage or port which opens into the combustion-chamber and which is provided with a closing valve or slide, in combination, substantially as set forth.
